Primary Examiner — Bridget L Eland(74) *Attorney, Agent, or Firm* — Gardere Wynne Sewell LLP; Robert J. Ward**CLAIM**

The ornamental design for a medical dilator, as shown and described.

DESCRIPTION

FIG. 1 is a perspective view of a medical dilator in accordance with the present invention;

FIG. 2 is a front elevation view of the medical dilator shown in FIG. 1;

FIG. 3 is a top plan view of the medical dilator shown in FIG. 1; and,

FIG. 4 is a bottom plan view of the medical dilator shown in FIG. 1.

The broken line circles shown in the FIG. 1, FIG. 2, and FIG. 3 views that are immediately adjacent the claimed areas represent the bounds of the claimed design. The evenly spaced broken lines shown in FIG. 1 and FIG. 2 are superimposed on a continuous surface and directed to environment. The broken line circles and evenly spaced broken lines form no part of the claimed design.
